SIGNALING SYSTEM

Morris E. Griffins, Western Springs, Ill., assignor
to Associated Electric Laboratories, Inc., Chi-
cago, Ill., a corporation of Delaware

Application June 27, 1936, Serial No. 87,631

9 Claims. (Cl. 177—360)

The present invention relates in general to signaling systems and more in particular to fire alarm systems such as are commonly used to announce the location of fires by coded blasts of a 5 whistle or siren.

In the ordinary fire alarm system a number of alarm boxes are located at strategic points throughout the city, and each box is provided with means for sending a distinctive signal to a 10 central point where control apparatus is provided capable of responding to any signal to operate the siren in accordance therewith and thus announce the location of the fire, or more accurately, the location of the box from which the 15 alarm is sent.

This type of system has given satisfaction, but the number of alarm boxes that can be provided is necessarily limited, and it happens frequently that when a fire occurs the person discovering it 20 will not be close to an alarm box and will find it quicker and more convenient to telephone the alarm to the central exchange. Most telephone operating companies list a fire number in their directories.

The invention is especially directed to the situation outlined in the foregoing, and has for its object the provision of apparatus for installation at a telephone exchange to supplement the alarm box system, and afford means by which an operator receiving a fire call can quickly bring about the proper operation of the siren and cause the same to announce the location of the fire in the same manner as when controlled from an alarm box.

A more detailed explanation of the invention and the various features thereof will be given hereinafter, reference being had to the accompanying drawings, in which—

Fig. 1 is a diagrammatic circuit drawing showing certain equipment of an automatic telephone exchange equipped with the invention; and

Fig. 2 is a diagrammatic circuit drawing of the apparatus for controlling the siren.

The invention will be described on the assumption that it is installed in an automatic telephone exchange. As is well known, such an exchange will have one or more operators to handle information calls, complaint calls, etc., and it will be assumed that these operators also handle the 45 fire calls. As each operator has a number of outgoing trunks over which she can extend outgoing calls, no additional automatic equipment has to be installed ordinarily, as the system of outgoing trunks can be used to give access to the siren control apparatus.

Referring to the drawings, the reference letter J in Fig. 1 indicates a jack which terminates an outgoing trunk at an operator's position. The reference letter P indicates a portion of a cord circuit at the operator's position. Only the call-

ing device or dial CD and a key K for connecting it across the cord are shown.

The trunk line shown extends to a first selector S1, which along with other similar selectors has access to second selectors such as the selector S2. 5 These selectors may all be of the well known Strowger vertical and rotary type. The trunk line J and the selectors S1 and S2 are primarily used for completing telephone connections.

There may be other selectors beyond the 10 second selectors, third selectors, for example, but for convenience the siren control apparatus has been shown as accessible from the second selectors. As can readily be seen from the drawings the first, second, and fourth levels are used for 15 this purpose, while the other levels not shown are used in regular telephone connections.

The siren control apparatus is shown in Fig. 2 and comprises the busy key BK, a number of relays, three so-called minor switches MS1, MS2, 20 and MS3, and two rotary switches, RS1 and RS2. As this apparatus is all of well known design and in common use in telephone systems it need not be described in detail.

The siren is not shown in detail but is indicated by a rectangle labeled SR which is located at the fire station. The invention is not concerned with the details of the siren itself, there are a number of different types on the market, and it will be sufficient to state that when the 25 coding relay 113 energizes it closes a circuit at 173 for actuating the siren over the conductors 170 and 172 extending from the telephone exchange to the fire station. If the siren equipment includes a normally energized relay that 30 falls back to actuate the siren then the leads to the siren are connected to terminals 171 and 172 instead of to 170 and 172. These terminals, therefore, afford a convenient means of adapting the control apparatus to any type of siren equipment. The circuits from the alarm box apparatus, not shown, may tie in either at terminals 35 170-172 or at terminals on the siren equipment.

It will be assumed now that a fire is reported by telephone to the operator having the equipment shown in Fig. 1. Upon receiving the report the operator will check the reported location of the fire against a map or chart with which she is provided so as to determine the nearest alarm box, which may be, for example, box No. 35. It 45 will be understood that the boxes are numbered in accordance with the code signals which they are adapted to transmit to operate the siren. The operator will then plug into a jack such as J with a cord such as P, operating key K thereof, 50 and will dial the number required to reach the siren control apparatus and register the code digits corresponding to the location of the fire. The first two digits of this number are the digits 55 1 and 4, serving to operate the selectors S1 and S2.

S2, respectively, and the last two digits are the code digits 3 and 5. Hence the complete number is 1435.

On plugging the cord P into the jack J the first selector S1 is prepared for operation in the usual manner, and when the calling device CD is operated in accordance with the first digit 1 the selector will raise its shaft carrying wipers 21-23 to the first level and will rotate in on this level in search of an idle second selector. The operation of the first selector will not be given in detail as the circuit is not shown, but it may be stated that the operation is the same as that of the second selector S2, which will be explained.

Assuming that the second selector S2 is idle, there will be battery potential on the test contact 24, and when the test wiper 21 of the selector S1 picks up this battery potential the test relay will energize and stop the rotation of the switch with wipers 21, 22, and 23 in engagement, respectively, with bank contacts 24, 25, and 26. Relay 32 of the second selector energizes in series with the test relay of the first selector. The operation of the test relay in the first selector extends the trunk through to the wipers 22 and 23 and a circuit is therefore established for the line relay of the second selector S2. Upon energizing, line relay 30 closes a circuit for the slow-acting release relay 31. The latter relay on energizing grounds the incoming test circuit at 38, thereby closing a local holding circuit for relay 32 and also closing a holding circuit for the test relay of the selector S1. Ground applied to the test contact 24 and its multiples in the banks of the other first selectors maintains the second selector S2 in busy condition. The release relay 31 also connects the upper winding of the test relay 33 to the test wiper 51 at 39, and prepares a circuit for the vertical magnet 34 at 40. It will be noted also that the ground at 38 serves to energize the lower polarizing winding of the test relay 33. This relay, however, does not operate at this time.

When the operator dials the next digit 4 of the number the line relay 30 deenergizes four times and transmits four impulses to the vertical magnet 34, the circuit including 45, 37, 40, and the winding of the vertical magnet. The vertical magnet responds to these impulses and raises the shaft carrying the wipers 51, 52, and 53 step by step to the fourth level of the banks. On the first step of the switch shaft the off-normal contacts labeled "On" in the drawing are all shifted and circuits are prepared for the release magnet 36 and for the rotary magnet 35. Also the circuit of the upper winding of the slow-acting relay 32 is broken; but this relay holds up while the line relay 30 is sending impulses to the vertical magnet 34, as the lower winding of the relay is connected in parallel with the vertical magnet.

When the impulses cease, the wipers come to rest opposite the fourth level, and an instant later relay 32 deenergizes, closing a circuit at 41 for the rotary magnet 35. Upon energizing, the rotary magnet rotates the switch shaft one step, bringing the wipers 51, 52, and 53 into engagement with the bank contacts 54, 55, and 56, respectively. The rotary magnet breaks its own circuit and falls back, whereupon its circuit is reclosed, but before the magnet can energize again test relay 33 energizes and breaks the rotary magnet circuit at 45, thereby definitely bringing the selector to rest. The circuit of the test relay extends from ground at 38 by way of the upper winding of the test relay, 39, 51, 54,

63, key BK, 131 and upper winding of relay 105 to battery. When the test relay 33 energizes, in addition to breaking the rotary magnet circuit at 45, the relay extends the test lead through at 42 and extends the talking conductors of the trunk through at 43 and 44, at the same time disconnecting the line relay 30. The line relay 30 and the release relay 31 accordingly fall back, but the test relay 33 remains operated from ground at the siren control apparatus as 10 will be presently explained, and the selector remains in operated position.

The talking conductors of the trunk are now extended by way of wipers 52 and 53, bank contact 55 and 56, and conductors 65 and 66, to the 15 line relay 100 of the siren control apparatus, and this relay accordingly energizes, closing a circuit at 125 for the slow release relay 101. On energizing, relay 101 prepares a stepping circuit at 126 for the minor switch MS1 and closes a circuit at 128 for relay 102. The closure of contact 128 also applies ground to incoming test conductor 61, which makes the siren control apparatus busy at the second set of bank contacts of the first level of the selectors such as S2. 25 Ground at 128 also extends by way of 127 and key BK to the incoming test conductor 63, which makes the siren control apparatus busy at the first set of bank contacts in the fourth level, and also provides a holding circuit for the second 30 selector S2 as hereinbefore mentioned. When the relay 102 energizes it closes a circuit for the lower polarizing winding of relay 111 at 132, but relay 111 does not operate at this time. Relay 102 also grounds the incoming test conductor 35 64 at 144 and grounds the incoming test conductor 60 at 129, thereby making the siren control apparatus busy at the first set of contacts in the first level and the second set of contacts in the fourth level of the second selectors. The 40 closure of contact 130 is not effective to operate relay 103 because the circuit of this relay has previously been opened at 128 by relay 101.

Returning now to the time when the siren control apparatus is first seized, it will be recalled that the circuit of the test relay of the selector S2 includes the winding of relay 105 of the signal control apparatus, and relay 105 is accordingly energized in series with the test relay. On energizing relay 105 closes a circuit 50 at 140 for the stepping magnet 118 of the minor switch MS3. Magnet 118 is accordingly energized and the wiper 160 of the minor switch is advanced one step into engagement with the first contact in its bank. Now, when relay 102 55 energizes a little later the circuit of relay 105 is broken at 131 and accordingly relay 105 falls back and breaks the circuit of stepping magnet 118, which thereupon deenergizes.

The operator may now dial the third digit of 60 the number, which is the first code digit 3. As a result the line relay 100 is deenergized three times and three impulses are transmitted to the stepping magnet 114 of the minor switch MS1, the circuit extending from ground at 125 by way 65 of 126, 143, 137, and winding of magnet 114 to battery. Magnet 114 responds to these impulses and advances the wiper 157 three steps into engagement with the third contact in its bank. The slow-acting relay 104 is energized in parallel 70 with the magnet 114 and holds up during the series of impulses. Upon the first step of the minor switch MS1, its off-normal contacts "on" are closed and a circuit is prepared for the release magnet 115. Also a new energizing cir- 75

cuit is prepared for relay 105, but this relay does not energize at the moment due to the fact that relay 104 has already operated. When the impulses for the first code digit cease, the minor switch MS1 comes to rest with its wiper 157 in engagement with the third contact in its bank and shortly afterwards the slow-acting relay 104 falls back. The new energizing circuit for relay 105 is thereupon closed, said circuit extending from ground at 128 by way of 135, lower off-normal contacts "on" of MS1, lower off-normal contacts "on" of MS2, and the lower winding of relay 105 to battery. On energizing, relay 105 again closes the circuit of stepping magnet 118 of minor switch MS3 at 160, and the magnet energizes to advance the wiper 159 into engagement with the second contact of its bank. The shifting of contact 139 of relay 105 is of no importance at the moment, but at 138 relay 105 prepares a holding circuit for its upper winding, and at 137 the relay shifts the impulsive circuit from the stepping magnet 116 of minor switch MS1 to the stepping magnet 116 of minor switch MS2.

The operator may now dial the last digit of the number, which is the second code digit 5. In response to the dialling of this digit the line relay 100 deenergizes five times and transmits five impulses to the stepping magnet 116 of the minor switch MS2. Stepping magnet 116 accordingly operates five times and advances wipers 158 and 159 into engagement with the fifth contacts of their respective banks. The slow-acting relay 104 energizes in parallel with the stepping magnet 116 and holds up during the series of five impulses. At 136 relay 104 breaks the circuit of stepping magnet 118 of minor switch MS3 and allows this magnet to deenergize. At 135 relay 104 breaks the initial energizing circuit for the lower winding of relay 105 and at the same time closes a circuit by way of 135 and 138 for the upper winding of relay 105, which maintains relay 105 energized. On the first step of the minor switch MS2, the off-normal springs are shifted and at the upper pair of off-normal contacts a circuit is prepared for the release magnet 117, while at the lower pair of off-normal contacts the initial energizing circuit for the lower winding of relay 105 is broken. When the impulses for the last digit cease, the slow-acting relay 104 falls back and breaks the circuit of relay 105 at 135. Relay 105 is slow-acting, however, and before it can restore another impulse is transmitted by way of 136 and 140 to the stepping magnet 118 of minor switch MS3. Wiper 160 is accordingly advanced into engagement with the third contact in its bank.

The complete number 1485 has now been dialled, and the last two digits of the number, or the code digits, have been registered on the minor switches MS1 and MS2. The wiper 157 of minor switch MS1 is now standing on the third contact in its bank and the wiper 158 of minor switch MS2 is standing on the fifth contact in its bank. Also it will be recalled that the wiper 160 of MS3 has been advanced to the third contact in its bank. Contacts 1 to 9 of the bank of wiper 157 of minor switch MS1 are multiplied in reverse order to contacts 2 to 9, in the bank of wiper 161 of rotary switch RS1, and contacts 1 to 0 in the bank of wiper 158 of minor switch MS2 are multiplied straight to contacts 12 to 21, inclusive, in the bank of wiper 161 of rotary switch RS1. These multiple connections are not shown in full but are indicated by the brack-

ets and heavy lines. It will be seen, therefore, that the seventh contact in the bank of wiper 161 will be marked with a ground potential and that the sixteenth contact in the bank of wiper 161 will be marked with a battery potential. The 5 ground potential on the seventh contact is obviously derived from the setting of grounded wiper 157 on its third contact, while the battery potential on the sixteenth contact is derived from the setting of wiper 158 on its fifth contact, 10 the wiper 158 being connected to battery through the lower winding of relay 105.

Continuing with the operation, when relay 105 falls back when its circuit is broken by the falling back of relay 104 at the end of the 15 dialling operation, it recloses the circuit for the lower polarizing winding of relay 111 at 139; and at 141 closes an initial energizing circuit for the stepping relay 112 of rotary switch RS1. This circuit extends from grounded wiper 164 20 in normal position, by way of the first contact in the bank of the wiper 164, fifth contact in the bank of wiper 159 of MS2, wiper 159, 141, 145, 154, 156, and winding of relay 112 to battery. On energizing relay 112 closes a circuit 25 for stepping magnet 120 and the latter upon energizing breaks the relay circuit at 156. The relay 112 accordingly deenergizes and breaks the magnet circuit, whereupon the magnet deenergizes in turn and advances the wipers 161—164 30 one step, at the same time reclosing the circuit of stepping relay 112. An automatic stepping circuit is now established which extends from the grounded wiper 164 by way of strapped contacts in the bank of this wiper, 154, 156, and 35 winding of relay 112 to battery. The relay 112 and magnet 120 accordingly interact in the well known manner and rapidly advance the wipers 161—164 of RS1 step by step in search of the first marked contact in the bank of wiper 161. 40

As stated hereinbefore, the contact which has been marked is the seventh contact, and when wiper 161 arrives at this point, therefore, a circuit is completed for relay 111, the circuit extending from grounded wiper 157, by way of the 45 third contact in the bank of said wiper, seventh contact in the bank of wiper 161, wiper 161, upper winding of relay 111, and resistance r to battery. Relay 111 operates over the foregoing circuit and at 154 opens the automatic stepping 50 circuit for stepping relay 112, closes a circuit for relay 106 at 153, grounds wiper 165 of rotary switch RS2 at 152, and prepares a circuit for the coding relay 113 at 150. Due to the opening of the automatic stepping circuit at 154, the operation 55 of rotary switch RS1 ceases for the moment.

When relay 106 operates responsive to the closure of its circuit by relay 111, it prepares a locking circuit for itself at 142, prepares a locking circuit for the release relay 101 at 143, also 60 opening the stepping circuit to the minor switches at the same point, breaks the initial energizing circuit for stepping relay 112 at 145, and at 146 closes a circuit for the interrupter relay 109. Relay 109 accordingly energizes and at 147 closes 65 a circuit for interrupter relay 110. The latter relay on energizing short circuits the winding of relay 109, which causes this relay to fall back and break the energizing circuit of relay 110, short circuiting the winding of the latter relay 70 at the same time. Relay 110 accordingly deenergizes and removes the short circuit from the winding of relay 109, permitting this relay to again energize. Accordingly it will be seen that relays 109 and 110 will operate alternately 75.

so long as the circuit of the former relay remains closed at 146. The function of interrupter relays 109 and 110 is to transmit impulses over wiper 162 by way of the back contact at 147 and the front contact at 148. Relays 109 and 110 are slow-acting and are preferably adjusted so that impulses are transmitted at the rate of two per second.

The impulses generated by interrupter relays 109 and 110 are effective to step the rotary switch RS2 over a circuit extending from ground at 147 by way of 148, 162, 176, and winding of the stepping magnet 121 to battery. The stepping magnet 121 is accordingly operated 15 at half-second intervals to advance the wipers 165 and 166 step by step over the contacts in their banks.

When wiper 165 reaches the second contact in its bank, at the end of the first impulse, a circuit is completed for the coding relay 113, the circuit extending from ground at 152 by way of wiper 165 and the second contact in its bank, conductor 179, wiper 163, conductor 175, 150, and winding of relay 113 to battery. Relay 113 accordingly operates and brings about the actuation of the siren SR by closing the contacts 113. Wiper 165 is preferably adjusted so that it does not break the circuit on passing from one contact to the next and accordingly the circuit for coding relay 113 is maintained while the wiper 165 is advancing from the second contact in its bank to the third, and the coding relay does not fall back until wiper 165 leaves the third contact in its bank at the end of the third impulse. It 35 will be seen therefore, that the coding relay 113 will be energized during two of the half-second steps of the rotary switch RS2, or for a total period of one second. The circuit of the coding relay 113 is open in the fourth, fifth, sixth, and 40 seventh positions of wiper 165 and accordingly the siren is silent for two seconds while the wiper 165 is passing through these positions.

In position 5 of wiper 165, however, a circuit is completed for advancing the rotary switch RS1. This circuit extends from ground at 152 by way of wiper 165, fifth contact in the bank of wiper 165, conductor 174, and winding of stepping relay 112 to battery. Relay 112 and magnet 120 are accordingly energized while wiper 165 is standing in 50 fifth position and deenergize when wiper 165 advances to sixth position. The deenergization of stepping magnet 120 advances the wipers 161—164 one step, so that the wiper 161 is moved from the seventh contact in its bank to the eighth. 55 This breaks the original energizing circuit of relay 111, but the relay remains in operated position due to the energization of its lower polarizing winding.

The siren is off for two seconds, corresponding 60 to four half-second steps of the rotary switch RS2, but when wiper 165 arrives at contact 8 in its bank the circuit for the code relay 113 is again closed and the siren is again actuated, remaining in operation for one second, or during 65 the time that wiper 165 is standing on the eighth and ninth contacts in its bank.

After sounding the siren for the second time, wiper 165 engages successively the tenth, eleventh, twelfth, and thirteenth contacts in its bank and 70 the circuit of the coding relay 113 is open in these positions of the wiper. In position 11 a circuit is completed as before for the stepping magnet 120 of the rotary switch RS1 and the resulting operation of this magnet causes the rotary switch RS1 to be advanced one more step,

bringing the wiper 161 from the eighth to the ninth contact in its bank.

Wiper 165 of the rotary switch RS2 next engages the fourteenth and fifteenth contacts in its bank; and in these positions of the wiper the circuit of the coding relay 113 is again closed and the siren is actuated for the third time. This completes the sounding of the siren in accordance with the first code digit.

When the wiper 165 engages the seventeenth contact of its bank a circuit is completed as before for the stepping relay 112, and the resulting operation of stepping relay 112 and stepping magnet 120 brings about the advance of the rotary switch RS1 one more step, the wipers moving from the ninth contacts in their respective banks to the tenth contacts. The movement of wiper 163 from its ninth contact to its tenth contact results in opening the circuit of coding relay 112, since the tenth and eleventh contacts in the bank of wiper 163 are not strapped. The tenth contact in the bank of wiper 161 is grounded, but the engagement of this grounded contact by wiper 161 has no effect at this time, as relay 111 is already energized.

Wiper 165 of rotary switch RS2 continues its advance at half-second intervals and on reaching the twentieth contact in its bank attempts to close the circuit of the coding relay 113, but the circuit cannot be closed owing to the fact that 30 wiper 163 of rotary switch RS1 is standing on an open contact, as previously mentioned. The siren accordingly is not sounded while wiper 165 of the rotary switch RS2 is in its twentieth and twenty-first positions.

When wiper 165 engages the twenty-third contact in its bank a circuit is again closed for the stepping relay 112 of rotary switch RS1. Stepping relay 112 and stepping magnet 120 accordingly energize, and deenergize when the circuit of the stepping relay is broken on the advance of wiper 165 from position 23 to position 24. The deenergization of magnet 120 advances the wipers of rotary switch RS1 to position 11. Since wiper 162 now engages its eleventh contact the next 45 impulse delivered by the interrupter relays 109 and 110 does not actuate the stepping magnet 121 of rotary switch RS2 but actuates the stepping relay 112 of rotary switch RS1. Relay 112 and stepping magnet 120 accordingly responds to this impulse and advance the wipers of rotary switch RS1 from position 11 to position 12, while the wipers of rotary switch RS2 remain standing in 50 position 24.

The next impulse from the interrupter relays 55 takes the usual path, as wiper 162 is now in position 12, and the rotary switch RS2 is advanced from position 24 to position 25. In position 25, wiper 166 engages a grounded contact and consequently the stepping magnet 121 is immediately energized and deenergized to advance the wipers of rotary switch RS2 to position 1. The wipers therefore go from position 24 to position 1 responsive to a single impulse, passing automatically through position 25.

It will be seen now that the circuit of the coding relay 113 has remained open while the wipers of rotary switch RS2 were passing from position 16 to position 1, or a total of ten positions, not counting position 25, which is passed without 70 stopping. Since the wipers stand in each of these ten positions for one-half second, the time thus measured off is equal to five seconds. To this interval there is added one-half second due to the fact that the rotary switch RS2 misses 75

one impulse while standing in position 24. The total interval, therefore, is equal to five-and-one-half seconds. This is the time prescribed for the spacing between code digits.

5 At the end of the next impulse delivered by the interrupter relays the wipers of the rotary switch RS2 are advanced to second position, and a circuit is again closed for the coding relay 113, which operates and begins sounding the siren 10 for the second digit of the code. The siren is sounded while wiper 165 is in positions 2 and 3, and is silent while the wiper passes through positions 4, 5, 6, and 7. In position 5 a circuit 15 is closed for the stepping relay 112 of rotary switch RS1 and by the operation of relay 112 and stepping magnet 120 the wipers of rotary switch RS1 are advanced to position 13.

In positions 8 and 9 of wiper 165 the siren is again sounded, and in position 11 the usual circuit is closed over which rotary switch RS1 is advanced to position 14.

In positions 14 and 15 of wiper 165 the siren sounds for the third time, and in position 17 a circuit is closed over which the rotary switch 25 RS1 is advanced to position 15.

In positions 20 and 21 of wiper 165 the siren is sounded for the fourth time, and in position 23 the rotary switch RS1 is advanced from position 15 to position 16. Wiper 161 is now in engagement with the second marked contact in its bank, but the arrival of wiper 161 thereat has no effect on relay 111.

The rotary switch RS2 continues through position 24 to position 1, passing up position 25 in the manner previously explained. On advancing from position 1 to position 2, the circuit of the coding relay is again closed and the siren is sounded in positions 2 and 3. This makes five times that the siren has been sounded in succession and completes the sounding of the second digit of the code. The complete signal designating the location of the fire has now been sounded, this signal comprising three blasts of the siren followed by five blasts, corresponding to the code digits 3 and 5.

While the siren is sounding the lamp L, visible to the operator, is flashing off the code signal. Although the siren need not be at the telephone exchange, and usually would not be, the operator generally will be able to hear it and the lamp L is chiefly useful as an assurance that the control apparatus is working all right in case the siren should not sound.

When the siren begins to sound the operator 55 may withdraw her plug, as no further operations on her part are required. On withdrawal of the plug the line relay 100 falls back and at the front contact 125 breaks the initial energizing circuit of release relay 101. At the back contact 125, 60 however, a new circuit for relay 101 is established by way of 125, 126, and 143, relay 106 being now energized, and the release relay 101 is held up, as well as relay 102. Thus the apparatus is maintained in operated position contingent on relay 65 106 remaining operated, which it does until the code has been sounded four times.

The rotary switch RS2 continues to step along and when wiper 165 engages the fifth contact in its bank the circuit is closed in the usual manner for stepping relay 112, and this relay operates and closes a circuit for the stepping magnet 120. At the same time relay 112 closes a circuit for relay 105 which extends from ground at 155 by way of 151, wiper 161 and the sixteenth contact 70 in its bank, fifth contact of the bank of wiper 75

158 and said wiper now in engagement therewith, and the lower winding of relay 105 to battery. On energizing, relay 105 closes a circuit at 140 for the stepping magnet 118 of minor switch MS3, thereby advancing wiper 160 into engagement with the fourth contact in its bank. This operation closes a locking circuit for relay 106, said circuit including the grounded wiper 160 and contact 142 of relay 106. Relay 105 also breaks the circuit of the lower polarizing winding 10 of relay 111 at 139 and also connects ground to the upper winding of this relay. The circuit of the lower winding of relay 111 being open and the upper winding of this relay short circuited (relay 112 is still operated) the relay deenergizes. 15

On falling back relay 111 prepares an automatic stepping circuit for the rotary switch RS1 at 154, and opens the energizing circuit of relay 106 at 153. Relay 106 does not fall back, however, because it has previously been locked at the grounded wiper 160 of minor switch MS3. Relay 111 also takes the ground off from wiper 165 at 152, but the wiper remains grounded at wiper 160 of the minor switch MS3. In addition to the foregoing, relay 111 opens the circuit of the coding 25 relay 113 at 150 and breaks the circuit of relay 165 at 151. Relay 105 accordingly deenergizes, opens the circuit to magnet 118 of minor switch MS3, and closes the circuit of the polarizing winding of relay 111. The latter relay remains deenergized, as there is no circuit at present established for its upper winding.

The foregoing operations involving the operation of relay 105 and the deenergization of relay 111 all occur while the wipers of the rotary switch 35 RS2 are standing in fifth position. When the wipers advance from fifth position to sixth position wiper 165 breaks the circuit of stepping relay 112 and this relay and stepping magnet 120 deenergize, advancing the rotary switch RS1 from the sixteenth to the seventeenth position. On the falling back of the stepping magnet 120 the stepping relay 112 immediately energizes again in an automatic stepping circuit which was established by the deenergization of relay 111, this 40 circuit extending from the grounded wiper 164 by way of strapped contacts in its bank, 154, 156, and winding of relay 112 to battery. Relay 112 and magnet 120 now interact and rapidly step the rotary switch RS1 to position 22, where 50 the switch comes to rest for the time being. The stopping of the switch in position 22 is due to the fact that the automatic rotary circuit is open at this point, contacts 22 to 25 being included in a different circuit which is now open at the off-normal contacts of minor switch MS3, as well as at contact 145 of relay 106.

The continued stepping of rotary switch RS2 now brings about the slow advance of rotary switch RS1 for the purpose of introducing a long 60 time interval before the sounding of the next code signal begins. On reaching position 11, wiper 165 closes the circuit of stepping relay 112 and the rotary switch RS1 is advanced from position 22 to position 23. The circuit is again closed 65 in position 17 of wiper 165, advancing the wipers of RS1 from position 23 to position 24. The circuit is again closed in positions 23 and 5 of rotary switch RS2, and the two additional steps of rotary switch RS1 carry the wipers from position 70 24 to position 25 and then from position 25 to position 1. Rotary switch RS1 cannot at this time automatically leave position 1 because the circuit for relay 112 by way of wiper 164 and wiper 159 of minor switch MS2 is open at con- 75

tact 145 of relay 106. When the rotary switch RS2 reaches position 11 the circuit for stepping relay 112 is closed once more and the rotary switch RS1 is advanced from position 1 to position

5 2. The automatic stepping circuit by way of wiper 164, 154, and 156 is now established, and the rotary switch RS1 advances rapidly from position 2 to position 7, where wiper 161 engages the first marked contact in its bank and brings 10 about the energization of relay 111.

When the rotary switch RS2 reaches position 14 the circuit of the coding relay 113 is again closed, and thus the operation of the siren in accordance with the registered code digits begins 15 again. The operation of the siren the second time is the same as has been previously described and consequently need not be explained in detail. It will be noted that the sounding of the second signal begins with the rotary switch RS2 in position 14 instead of in position 2, but otherwise 20 the operation is the same.

At the end of the second complete code signal relay 105 operates in the manner previously explained and advances the minor switch MS3 from 25 the fourth contact in its bank to the fifth contact. At the end of the third complete code signal relay 105 operates again and steps the minor switch MS3 ahead one more step so that wiper 160 advances from the fifth contact in its bank 30 to the sixth contact. At the end of the fourth complete code signal, when relay 105 operates it advances minor switch MS3 again, and the wiper 160 moves from the sixth contact to the seventh contact. This operation breaks the locking circuit 35 of relay 106. The energization of relay 105 also brings about the deenergization of relay 111, as previously explained, and when relay 111 falls back relay 106 falls back also, due to its locking circuit having been broken at the minor switch 40 MS3. The deenergization of relay 106 stops the operation of interrupter relays 109 and 110. The deenergization of relay 106 also opens the circuit of the release relay 101, whereupon this relay and relay 102 fall back. The deenergization of relays 45 101 and 102 removes ground from the incoming test conductors 50, 61, 63, and 64, and the removal of ground from the test lead 63 breaks the holding circuit for the selector switches S1 and S2, which switches accordingly release in the 50 well known manner. The deenergization of relay 101 also completes circuits for the release magnets 115, 117, and 119 of minor switches MS1, MS2, and MS3, respectively, and the minor switches are accordingly restored to normal. The 55 rotary switches RS1 and RS2 are restored through the medium of their wipers 164 and 166. As regards the rotary switch RS1, it will be observed that the falling back of relay 106 and the restoration of minor switch MS3 connects all of the 60 contacts in the bank of wiper 164 in multiple except the first contact, and accordingly regardless of the instant position of wiper 164 the automatic stepping circuit including wiper 164 and contacts 154 and 156 will be established and will remain 65 in effect until position 1 is reached. As regards the rotary switch RS2, the falling back of relay 106 grounds the strapped contacts in the bank of wiper 166 and accordingly the stepping magnet 121 operates automatically until the switch 70 reaches position 1. Thus all the apparatus is restored to normal position.

The usual procedure in the case of a fire alarm is to sound the siren four times. That is, the complete code number corresponding to the location of the fire is sounded four times by means

of the siren. In certain cases, however, as in the case of a fire drill, it may be desired to sound a code signal only once. The manner in which this is accomplished will now be explained.

The operator plugs into the jack J the same 5 as before and dials the number, which in this case comprises the digits 1 and 1, followed by the two digits of the code. When the first digit 1 is dialled the selector S1 is operated as before explained to connect with a second selector such 10 as the second selector S2. Responsive to the dialing of the second digit 1, the second selector S2 raises its wipers to the first level, and then automatically rotates the wipers one step to bring the wipers into engagement with the first set of 15 bank contacts in the first level. This set of contacts gives access to the siren control apparatus shown in Fig. 2 the same as the first set of contacts in the fourth level, except that the test lead 64 is employed instead of the test lead 63. 20 As the result the test relay 33 of the second selector is energized over a circuit which includes the test wiper 51, test lead 64, contacts of key BK, contact 144, and resistance r to battery. It will be noted that since this circuit is completed 25 to battery through the resistance r instead of through the upper winding of relay 105, the relay 105 is not operated upon the seizure of the siren control apparatus and the minor switch MS3 does not receive a preliminary step. The line relay 100 energizes as in the preceding case, followed by the energization of relays 101 and 102 with results as previously explained.

The operator may now dial the two code digits. 30 In the course of the registration of these digits the relay 105 is operated, and this relay cooperating with relay 104 advances the minor switch MS3 to the second contact in its bank. The siren is now sounded in the manner previously explained and on the completion of the operation 40 relay 105 is operated again, advancing the minor switch MS3 to the third contact in its bank. The operation of relay 105 at the end of the code operation of the siren causes relay 111 to fall back and now the deenergization of relay 111 brings 45 about the deenergization of relay 106. This is due to the fact that the minor switch MS3 has only been advanced to the third contact in its bank and no locking circuit for relay 106 has been established. It follows that the equipment releases and the code is only sounded for a single time.

The apparatus is arranged so that single-digit codes can be sounded as well as two-digit codes. An example of a single-digit code is the signal 55 which is commonly given at twelve o'clock noon. This noon signal usually comprises a single blast of the siren. The manner of operating the siren to give the noon signal will now be explained briefly.

The number which the operator is required to dial in order to sound the noon signal is the number 1101. The first two digits of the number serve to operate the selectors S1 and S2, and the latter selector seizes the control apparatus at the 65 first set of contacts in the first level in its banks. Seizing the control apparatus over this route rather than by way of the first set of contacts in the fourth level determines that the signal will be sounded only once. This feature of the 70 invention has just been explained. The registration of the last two digits takes place in the manner previously described, and when the third digit of the number is dialled the wiper 157 of minor switch MS1 is set on the tenth con- 75

tact in its bank. The dialling of the final digit in the number sets the wiper 158 of minor switch MS2 on the first contact in its bank.

As soon as the number has been dialled the control apparatus starts to function and rotary switch RS1 hunts for the first marked contact in its bank. It will be seen, however, that since the tenth contact in the bank of minor switch MS1 is dead, that is, not connected up, none of the contacts 2 to 9, inclusive, in the bank of wiper 161 will be marked with a ground potential, and consequently the relay 111 will not pull up until the rotary switch RS1 arrives in tenth position. In this position wiper 161 engages a grounded contact and consequently relay 111 is energized; but at the same time it will be seen that wiper 163 has also reached the tenth contact in its bank, and since this contact is open the circuit for the coding relay 113 cannot be closed. Thus, the first code digit is omitted. The rotary switches RS2 and RS1 continue to function and in position 12 of rotary switch RS1 the code relay 113 is operated and the siren is sounded. The twelfth contact in the bank of wiper 161 is the contact that has been marked by the setting of wiper 158 of minor switch MS2, and accordingly when the switch RS2 again closes the circuit of the stepping relay 112, relay 105 will be energized, relay 111 will be deenergized, and further actuation of the siren will cease. Thus it will be seen that the dialling of the specified number 1101 will produce a single blast of the siren.

The function of the busying key BK will now be explained. The interrupter relays 109 and 110 constitute a somewhat critical part of the apparatus as they have to transmit impulses reliably and at a constant frequency. These relays, therefore, may occasionally require to be inspected and adjusted. For this reason a second set of interrupter relays comprising relays 107 and 108 is provided. This second set of interrupter relays is ordinarily not in use and may be adjusted at any time without interfering with the operation of the rest of the equipment. In case the interrupter relays 109 and 110 should require attention, however, the man who is working on the equipment will first operate the busy key BK. The operation of this key arranges matters so that if the control apparatus is seized by a second selector such as S2 the interrupter relays 107 and 108 will be used instead of the interrupter relays 109 and 110. The manner in which this is accomplished will now be briefly explained.

Assuming that the operator dials a number to sound the siren for a regular fire call, a second selector, S2, for example, will be raised to the fourth level and will rotate in on this level with the test wiper 51 searching for a battery potential. Since key BK has been operated the test lead 63 will now be open and consequently the switch is unable to stop on the first set of contacts but rotates over to the second set of contacts. On the second test contact in the fourth level the test wiper 51 finds a battery potential over test lead 60 and through contact 129 and the winding of relay 103. Accordingly the test relay 33 of the selector pulls up in series with relay 103, the latter relay energizing also. On the extending through of the line conductors by the operation of test relay 33, the line relay 100 operates, followed by the operation of relays 101 and 102. Relay 101 on energizing closes a locking circuit for relay 103 by way of 128, 127, and

133, from which it will be seen that relay 103 will remain energized throughout the remaining operations of the control apparatus. The substitution of the interrupter comprising relays 107 and 108 for the interrupter comprising relays 109 and 110 takes place at armature 134 of relay 103. It will readily be seen that with relay 103 operated, when relay 106 pulls up it will close a circuit through to relay 107 rather than to relay 109.

It may happen that after an operator has dialled some fire alarm number and the siren has started to sound, she will desire to stop the siren, as for example, if later information should show that the fire call was a false alarm. The operator might also accidentally dial the wrong number. Such a situation will arise infrequently, but nevertheless it is desirable to provide means for readily stopping the siren if it should become necessary to do so. The manner in which this is done will now be explained.

The operator will withdraw the plug P from the jack in use, jack J, for example, if she has not already done so, and will plug into the jack of another outgoing trunk. After plugging in the operator dials the digits 1 and 2, which operate a first selector similar to S1 and a second selector similar to S2 to seize the siren control apparatus by way of the second level of the second selector bank. The first test contact in the second level is not now guarded from the siren control apparatus, so the second selector in use will stop even though the first operated second selector is being held up by the operating siren control apparatus.

More in detail, when the operated second selector rotates in on the first set of contacts in the second level the test relay such as 33 will operate over a circuit including the test lead 62, the upper winding of relay 106, and the upper winding of relay 105 to battery. The energization of the test relay brings the selector to rest in the usual manner. Current flow over the test circuit deenergizes relay 106 by differential action, and energizes relay 105. The latter relay brings about the deenergization of relay 111 if the same is in energized condition at the time. Relay 106 cannot reoperate over its upper winding as this winding has few ampere turns, sufficient only to balance out enough of the lower winding to make the relay fall back. Relay 106, on falling back, breaks the locking circuit of relay 101 and closes a circuit for relay 104 and magnet 116 at 143. Relay 104, on energizing, closes a holding circuit for the selectors from ground at 128 by way of 135, 138, upper winding of relay 106, and test lead 62. At the selectors this circuit is grounded until the release relay of the second selector falls back and after that includes the high resistance locking windings of the test relays, so relay 106 remains unoperated. A short interval after its locking circuit is broken relay 101 deenergizes, followed by the deenergization of relay 102. These relays falling back remove ground from all the incoming test leads, including test lead 62, and both switch trains are released. Relay 105 also restores at this time. Relay 104 falling back breaks the circuit of relay 104 and magnet 116, and closes the release magnet circuits of the minor switches. The rotary switches restore as previously explained.

While the invention has been described as installed in an automatic telephone system, it will be appreciated that it could readily be installed in a manual system. When installed in a manual

system a number of different jacks would be used at some operator's position to give access to the control apparatus over the requisite number of different routes, and the operator would be provided with a special dial plug and calling device.

The invention having been described, what is considered to be new and is desired to have protected by Letters Patent will be set forth in the appended claims.

10. What is claimed is:

1. In a signaling system, a signal, signal control apparatus, an automatic switch, means for operating said automatic switch to extend a connection to said apparatus over either of two different routes, means included in said apparatus and selectively controlled over the extended connection for operating said signal in accordance with any desired one of certain code signals, and means included in said apparatus for automatically controlling the number of times the code signal is to be repeated in accordance with the route used for the connection.

2. In a signaling system, signal control apparatus, switching means for extending a connection to said apparatus, means for causing said connection to be extended over either of two different routes, means included in said apparatus and selectively controlled over the extended connection for operating a signal, a pair of timed impulse generators forming part of said last means, and means depending on the route over which the connection is extended for determining which one of said generators is to be used for signal operation.

3. In a signaling system, a signal, signal control apparatus, two routes over which said apparatus may be seized, an automatic switch, means for operating said switch to extend a connection to said apparatus over either of said routes, means 40 in said apparatus controlled over said connection for operating said signal in accordance with a particular code, and additional means in said apparatus operated over the route used for controlling in accordance with the route used the number of times the code is to be transmitted by said signal.

4. In a signaling system, a signal, signal control apparatus, two routes for extending a connection to said apparatus, means in said apparatus controlled over one of said routes for operating said signal to transmit the desired code and for repeatedly actuating said signal in accordance with the desired code a predetermined number of times, and means in said apparatus responsive to seizure over the other of said routes for stopping the transmission of the code signal at any time prior to the completion thereof.

5. In a signaling system, signal control apparatus, means for selectively controlling said apparatus, said apparatus comprising a first progressively movable switch, means for advancing said switch step by step, a second progressively movable switch, a signal, a signal control circuit including said first and second switches, means including said first switch for alternately closing said signal control circuit and a circuit for the advancing means of said second switch, means including said second switch operated after a predetermined advance thereof for preventing the continued advancement of the first switch from closing said control circuit, said apparatus operated responsive to said selective control for de-

termining the number of cycles through which said switches are operated to close said signal control circuit.

6. In a signaling system, a signal, signal control apparatus, means for seizing and operating said apparatus to thereby control the operation of said signal, said apparatus comprising a first and a second step-by-step switch, a source of timed impulses, a circuit for advancing said first switch including said source and a wiper of said second switch, a circuit for advancing said second switch including a wiper of said first switch, and a signal control circuit including serially related wipers of both of said switches for controlling the operation of said signal.

7. In a signaling system, a signal, signal control apparatus, means for seizing and controlling the operation of said apparatus, said apparatus comprising a first and a second step by step switch, a source of current impulses, a circuit for advancing the first switch including said source and a wiper of said second switch, a circuit for advancing the second switch including a wiper of the first switch, a relay controlled through a wiper of the second switch, a signal control circuit including serially related wipers of both said switches and contacts of said relay, and means operated by said seizing and controlling means for determining the number of cycle operations of said switch wipers to control said signal control circuit.

8. In a signaling system, two registers, means for setting said registers over any one of a plurality of routes, a first and a second rotary switch, means for controlling the advancement of said second rotary switch under alternate control of said registers, means for controlling the advancement of said second rotary switch under control of said first rotary switch each time after it is controlled by one of said registers, a signal, a control circuit for operating said signal, means including wipers of said rotary switches for completing said circuit in accordance with the setting of said registers, and means controlled over the route used in setting said registers for determining the number of times said signal is to be operated to repeat the registration in accordance with the setting of said registers.

9. In a signaling system, two registers, means for setting said registers over either of two routes, a counting switch, means for operating said counting switch to find the setting of said registers, multiple connections between the bank of one register and a section of the bank of said counting switch, multiple connections between the bank of the other register and a different section of the bank of said counting switch, a signal, an operating circuit for said signal, a coding relay, means for operating said relay over one of the multiple connections of said first set of multiple connections to close said operating circuit when said counting switch finds the setting of the first of said registers, and means for deenergizing said coding relay to open said operating circuit when said counting switch finds the setting of the second of said registers over the second set of multiple connections, and control means dependent upon the route over which said registers are set for determining the number of times the counting switch finds the setting of the registers to control said signal circuit.

MORRIS E. GRIFFINS.
